ELECTRONIC TIMING DEVICE

Robert B. Leighton, Altadena, Calif., assignor to
the United States of America as represented
by the United States Atomic Energy Commis-
sion

Application September 26, 1950, Serial No. 186,828

4 Claims. (Cl. 250—36)

1

This invention relates to electronic timing devices and, more particularly, to a method and apparatus for indicating whether or not a plurality of events occur within a selected interval.

It frequently is necessary to determine whether or not a plurality of events occur substantially spontaneously or scattered, with respect to time. For example, in the art of geophysical prospecting by means of physically spaced charges, it is necessary to observe that the charges detonate within an interval which is small compared to the shock wave travel time to the observation point. Many other occasions arise in the various arts and sciences which require a similar determination of proximity in point of time.

The present invention discloses a simple and reliable electronic device which generates an audio tone having one selected frequency when impressed with a plurality of impulses, all of which occur within a selected time interval and an audio tone of different frequency when one or more of the impulses occur after the lapse of the selected time interval.

In a broad sense, the device of this invention in its preferred form comprises a pair of thytratrons both coupled to the source of impulses and so arranged that the first thytron is fired by the first impulse and locks out the second thytron for the selected interval so that subsequent impulses occurring in this interval are unable to fire the second thytron. Any impulse which occurs after the lock-out period fires the second thytron. Each of the thytratrons are coupled to the control grid of a third thytron arranged as a relaxation oscillator so that the relaxation rate of the third thytron has a first or a second value depending upon whether the first thytron alone is fired, or both the first and second thytratrons are fired. It follows that an audio translator coupled to the relaxation oscillator emits a steady tone of one frequency when all incoming impulses occur within the selected interval, and a different one if one or more impulses occur after the selected interval.

A better understanding of the invention will be afforded by the following specification which includes the accompanying drawing and a detailed description predicated thereon.

In the drawing, a preferred embodiment of the

2

invention is schematically illustrated. The arrangement illustrated utilizes a first thytron 3 and a second thytron 5 in a bias control circuit for the relaxation oscillator thytron 7.

Thytron 3 fires upon the impression of a first impulse on its grid 9. To this end, the thytron anode is provided with a positive potential by a connection through current limiting resistor 14 to the positive terminal of anode potential source 24. In order to generate a positive potential for application to the second thytron, the cathode 10 of tube 3 is connected to a common unipotential conductor, hereinafter for convenience termed "ground", through cathode resistor 13 and bias potential source 15. Cathode resistor 13 is shunted with a capacitance 16 in order not to degenerate the incoming impulse applied between grid and cathode and also to prevent overshooting when thytron 3 fires which might fire thytron 5. The grid of thytron 3 is impressed with an initial static negative bias through grid leak resistor 17. The thytron grid and cathode are coupled to input terminals 19 and 21 by means of coupling condenser 23 and ground, respectively. Thus far, an operable single stage thytron circuit is described which will fire upon the impression on the grid of a positive pulse of firing magnitude.

In the fired or conducting condition of thytron 3, the cathode acquires a positive potential. This positive potential is impressed across the grid-cathode space of relaxation oscillator thytron 7 thereby raising the rate of oscillation. Thus it follows that upon the occurrence of a first positive pulse, the audio translator 26 coupled to the relaxation oscillator commences to generate and maintains a distinctive audio tone.

Thytron 3 remains in the fired condition after being triggered so that in the absence of other effects, the audio tone generated by the third thytron remains constant.

In order to obtain an indication as to whether or not all succeeding impulses fall within a selected time interval measured from the occurrence of the first impulse, the thytron 5 and the storage network comprising condenser 27 and adjustable resistor 29 are provided. Thytron 5 is provided with anode potential through anode load resistor 31. The control or

igniting grid 33 is coupled to input terminal 19. The screen grid 35 is connected to storage network 27-29 and through cathode resistor 13 to the negative potential source 15. The control grid is impressed with a static negative bias by source 37.

It is to be noted that, although the firing grids of both thyratrons 3 and 5 are connected to the same negative value, and the same applies to the screen grids, the bias source in the cathode leg of thyratron 3 substantially reduces the effective negative bias on this tube so that tube 3 can fire, but tube 5 has such a high negative bias that it is locked out for the first impulse. The anode of thyratron 5 is connected to the grid of relaxation oscillator thyratron 7 so that if tube 5 fires, the grid bias of tube 7 is lowered thereby decreasing the rate of oscillation. The screen grid potential of tube 5 is substantially increased in the positive direction by the firing of tube 3, because it is then connected substantially directly to the low end of resistor 14.

It follows from the foregoing that upon the occurrence of a first positive impulse, thyratron 3 is fired thereby sharply decreasing its anode potential due to the potential drop through resistor 14. The negative pulse thus generated is stored in network 27-29 for an interval determined by the values of 27 and 29. The rate of dissipation of the negative charge from grid 35 of tube 5 determines the selected interval before tube 5 can be fired by a positive input impulse. During this interval, thyratron 5 is inactivated and cannot be fired. However, in the event a positive impulse arrives after the selected interval, tube 5 fires thereby decreasing the potential on the grid of the relaxation oscillator and causing a distinctive audio tone lower in frequency to be generated by translator 26.

An example of component types and values which can be used in a practical embodiment of the invention is shown on the drawing. It is to be understood that the selection of component types and values is representative and for convenience only, and that many other types of components with suitable values can be used. Further, it is apparent that other well-known types of tone generators can be substituted in an obvious manner for thyratron 7. Accordingly, since the invention admits of many modifications and variations, it is to be considered limited only by the scope of the appended claims.

What is claimed as new and desirable to be secured by Letters Patent of the United States is:

1. Apparatus for indicating whether or not a plurality of impulses occur within a selected time interval comprising a tone generator having a frequency dependent upon the magnitude of a potential impressed thereon; first bias generating means responsive to a first impulse for generating a first value of positive potential and a negative impulse, and means for electrically impressing said first value of positive potential on said tone generator; second bias generating means for generating a negative going potential; means for impressing said negative going potential on said tone generator; a storage network having a selected period, means for impressing said first bias generating means negative impulse on said network and means electrically connecting said network to said second bias means for inactivating the same for the selected interval after activation of said first bias generating means by a first input impulse.

2. Apparatus for indicating whether or not a plurality of impulses occur within a selected time interval, comprising first potential generating means for generating a positive going potential and a negative going potential in response to the impression thereon of a positive impulse, second potential generating means for generating a negative going potential, means for impressing input impulses on both the first and second means, a tone generator adapted to generate a tone having a frequency dependent on the magnitude of a potential impressed thereon, means for impressing said positive going potential on the tone generator to change the frequency thereof upon the occurrence of a first input positive impulse, means for impressing the first potential generating means negative going potential on the second potential generating means to inactivate the same for a duration which is a function of the parameters of the impressing means, and means for coupling the second potential generating means to the tone generator so that the occurrence of an input positive impulse after said duration causes the generation of a negative going potential by the second potential generating means to be impressed on said tone generator to cause it to operate at a different frequency.

3. Apparatus for indicating the duration of occurrence of a plurality of impulses with respect to a selected time interval comprising a relaxation oscillator circuit and a first, and a second bias potential generating means, said relaxation oscillator circuit including a grid controlled electron discharge device, a circuit network connecting the electron discharge device to the first and second bias potential generating means, impulse input terminals coupled to said first and second bias potential generating means, said first bias potential generating means being adapted to generate a positive going bias and a negative going bias, means for impressing said negative going bias on a storage network, and means for connecting said storage network to said second bias potential generating means whereby a first positive impulse causes said relaxation oscillator to increase its frequency of oscillation and an input positive impulse occurring after the negative going bias is dissipated from said network causes the relaxation oscillator to decrease its frequency of oscillation.

4. In combination with an audio tone generator, a first thyratron trigger circuit and a second thyratron trigger circuit and at least the second thyratron being of the tetrode type, each of said trigger circuits having two conditions of stability, means coupling the igniting grids of both of said thyratrons to input impulse terminals, a resistor in series with the cathode of the first thyratron and an adjustable potential storage network in the anode circuit of said first thyratron, a resistor serially connected in the anode circuit of the second thyratron, means for impressing a static negative bias on said first thyratron and means for impressing a static negative bias of larger value on said second thyratron, a tone generator including a grid controlled electron discharge device, a resistor network connecting the grid of the electron discharge device to the cathode of the first thyratron, and a resistor network connecting the grid of the electron discharge device to the anode of the second thyratron, means electrically connecting the control grid of the second thyratron to the cathode of the first thyratron whereby the negative bias is reduced during a fired

condition of the first thyratron, a resistor-capacitor network connecting the second grid of the second thyratron to the anode of the first thyratron, said resistor of the resistor-capacitor network being adjustable, whereby said second grid is biassed negatively for an adjustable period after firing of the first thyratron, whereby a first incoming positive impulse fires the first thyratron and increases the frequency of the tone generator and any succeeding positive impulse occurring 10 after the selected period of said network fires the second thyratron and decreases the frequency of the tone generator.
